(57) CLAIM

The ornamental design for a container, as shown and described.

DESCRIPTION

FIG. 1 is a front perspective view of a beverage container, showing my new design;

FIG. 2 is a front elevation view thereof;

FIG. 3 is a top plan view thereof; and,

FIG. 4 is a bottom plan view thereof.

The broken lines shown are included for the purpose of illustrating the unclaimed portions of the article and form no part of the claim.

1 Claim, 3 Drawing Sheets

FIG. 1

FIG. 4
